UNITED STATES PATENT OFFICE.

CARL A. MATSON, OF LYNN, MASSACHUSETTS, ASSIGNOR OF ONE-HALF TO ALBERT M. HOYT, OF SWAMPSCOTT, MASSACHUSETTS.

HEEL BURNISHING OR FINISHING WHEEL.

1,091,364.

Specification of Letters Patent. Patented Mar. 24, 1914.

Application filed February 19, 1913. Serial No. 749,295.

To all whom it may concern:

Be it known that I, CARL A. MATSON, a citizen of the United States, residing at Lynn, in the county of Essex and State of Massachusetts, have invented new and useful Improvements in Heel Burnishing or Finishing Wheels, of which the following is a specification.

This invention relates to a wheel which is adapted to finish the edges of the heels of boots and shoes either by the wax treating operation or by burnishing the edges of said heels after they have been colored with suitable coloring material.

15 The object of the invention is to provide a wheel which will apply wax evenly to the edges of the heels of boots and shoes and which will also impart a rubbing and polishing and burnishing action to the edges of 20 said heels of boots and shoes when they are held against it.

Moreover, it is the object of this invention to provide a wheel of the character set forth which will have a continuous yielding 25 metallic periphery and which will thus accommodate itself to the different curves of the edges of boot and shoe heels.

Further it is the object of this invention to provide a wheel of the character set forth 30 which shall be cheap to manufacture and durable in its construction.

In wax treating the heels of boots and shoes by means of my improved wheel, the wax may be applied in a melted condition 35 to the periphery of the wheel and the superfluous wax removed therefrom by means of a scraper as described and set forth in my application Serial No. 734,507 filed December 2, 1912, or the wax may be applied by means 40 of a stick held against the periphery of the wheel or in any of the various ways in which wax has heretofore been applied to the surface of the work-rubbing wheel in this art.

45 It is desirable, in addition to rubbing the heel circumferentially thereof in the wax treating operation to also simultaneously rub the heel transversely thereof or in a direction preferably from the heel seat toward the top lift, and it is the object of this 50 invention to provide a wheel which shall perform such an operation upon the edges of boot and shoe heels which are applied to its periphery.

55 In addition to wax treating the edges of

boot and shoe heels by means of my improved wheel, the same may be used as a burnishing wheel pure and simple—that is, it may be used to impart a high luster to the edges of the heels of boots or shoes and 60 can be utilized without the wax if so desired, in which case a coloring material is employed, such as blacking, and the burnishing wheel is then utilized to polish or burnish the edge of the heel with this coloring 65 material thereon. In either case, whether by wax treating or by burnishing a colored heel, my improved burnishing wheel imparts a high luster and smooth finish to the edge of the boot or shoe heel to which it is applied. 70

The invention, therefore, consists in a heel burnishing and finishing wheel such as described in the following specification and particularly of the construction set forth 75 in the claims.

Referring to the drawings: Figure 1 is a plan view of a portion of a machine for wax treating, burnishing and finishing the edges of the heels of boots and shoes with my improved heel burnishing wheel attached thereto, the parts being broken away to save space. Fig. 2 is a sectional elevation taken on line 2—2 of Fig. 1, also broken away to save space, a shoe heel being shown 80 in dotted lines in the proper position relatively thereto. Fig. 3 is a detail elevation of a modified form of my improved burnishing and finishing wheel. Fig. 4 is a detail section of a portion of a wheel illustrating 85 another modified form of my invention. 90

Like numerals refer to like parts throughout the several views of the drawings.

In the drawings, referring to Figs. 1 and 2, 5 is a frame having a bearing 6 in which 95 is rotatably mounted a shaft 7 to which is attached a pulley 8 by means of which said shaft is rotated. My improved heel finishing and burnishing wheel 9 is attached to the front end of said shaft and embodies a 100 hub 10 which is fastened by a set-screw 11 to said shaft 7.

The periphery of the wheel 9 is formed by a flexible member, preferably consisting of a metallic strip 12 forming a helix, the median axial line of said helix extending in the same general direction as the axis of said wheel, one end of said metallic member being fastened, preferably by welding, to a ring 4, the other end of said metallic mem- 110

ber being fastened to an annular flange 15, which flange is fastened by means of screws 16 to a cylindrical flange 17 forming a part of the hub 10. The ring 4 fits in an annular recess 18 provided in a flange 13 and is fastened thereto by means of screws 14. The cylindrical flange 17 is provided with an annular recess 19 to receive and center the flange 15. The flange 13 is provided with a hub 20 and is adjustably fastened to the hub 10 by means of a set-screw 21. The helical member 12 is thus fastened to a holder, said holder consisting of the hub 10 and the flanges 13, 15 and 17 and ring 4. It will thus be seen that the helical member 12 constitutes the periphery of the wheel 9 and is supported upon the holder hereinbefore described, which holder is fastened to the shaft 7 by the set-screw 11 and is rotated therewith. The adjacent convolutions of the helical member 12 substantially contact with each other and extend circumferentially around the periphery of said wheel, so that the wax cannot penetrate to the interior of the wheel when said wheel is used as a finishing wheel and the flanges 13 and 15 act to hold the convolutions of the helical member against lateral movement relatively to each other. By adjusting the flange 13 toward the flange 15, it will be seen that the different convolutions of the helical member 12 may be clamped against each other. The helical member 12 is preferably formed from a tube of proper size which is placed upon a lathe and cut so as to form the different convolutions of the helical member 12. Said helical member is then placed in a lathe and its convolutions clamped against each other by suitable means and the convex outer surface of the same is then turned thereon in said lathe. The outer edges of the helical strip 12 are rounded or chamfered off, thus forming between adjacent edges a helical groove 30. This chamfering or rounding off of the outer edges of the helical member prevents said edges from injuring or scratching the surface of the heel, and also where the convolutions are brought closely together there is formed between the adjacent rounded edges a helical groove 30 which acts as a guide or conductor for the melted wax and by means of this helical groove the melted wax will be distributed evenly throughout the entire periphery of the wheel, so that the wax will be laid in an even layer and supplied to the heel in even quantities during the finishing operation. The inner diameter of the helical member is made greater than the outer diameter of the flange 17, so that a space 22 is provided in the finished wheel which allows the different convolutions of the helix to yield or move inwardly toward the median axial line of the wheel without

abutting against said cylindrical flange 17, 65 unless said convolutions are displaced to an abnormal or unnecessary extent, whereupon said flange 17 will act as a stop to limit such displacement.

Suitable means for heating the wheel 9 is 70 provided, such as the gas pipe 23 (Fig. 2). It will be seen that the periphery of the wheel 9 is a continuous yielding metallic periphery and also that said periphery is resilient.

While I have described my improved wheel as having the helical member formed of metal, it will, however, be evident that any material which is hard as compared with leather and can, therefore, polish or 80 burnish the same when rubbed thereagainst is an equivalent of metal and may be used without departing from the spirit of my invention. Such a material may be found in fiber and may be used with very good results, although not so durable and satisfactory as metal.

It is evident that the periphery of the wheel as a whole will yield and conform to the varying cross sectional contours of the 90 edges of different heels of boots and shoes which may be applied thereto in performing the finishing and burnishing operation, and as the member 12 is formed as a helix it is evident that when the wheel is rotated there 95 will be a polishing action extending circumferentially of the edge of the heel and also a tendency to lay the fibers of the leather smoothly, by reason of the action of the helically disposed convolutions of the member 12 which thus stand at an angle and tend 100 to rub the edge of the heel from the heel seat toward the top lift.

In Fig. 3 I have illustrated a modified form of my invention in which a plurality 105 of strips of material 24, 25 and 26 extend entirely around the periphery of the wheel and are supported upon a holder 27 similar to the holder illustrated in Figs. 1 and 2. These strips of material each form a coil and the coils are arranged so that a convolution of each of said coils is located between convolutions of another of said coils, said coils being formed in the present instance of three different pieces of metal each forming a 115 helix and the three coils forming a triple helix. By this arrangement comparatively thin strips of metal can be used and obtain a steep inclination or pitch and it is thus possible to place the different convolutions 120 of the wire in contact with each other, making a continuous metallic periphery of a plurality of helical members.

In Fig. 4 another modified form of my invention is illustrated in which the helical member 28 is formed of a wire, said wire being supported upon a holder 29 in a manner similar to that described in relation to

the form of my invention illustrated in Figs. 1 and 2.

The cross sectional contour of the periphery of the work rubbing wheel is made so as to be convex in its normal form and when a heel having a straight edge or having a curved edge of a lesser degree than the curve upon which the periphery of said wheel is formed is being burnished or finished upon my improved burnishing wheel, the different convolutions of the helix forming the periphery of said wheel will yield so that the periphery of the wheel will conform to the shape of the edge of the heel which is finished thereon.

In using the wheel of my invention, the shoe is placed against it in the usual manner and where wax is utilized it is supplied to the wheel by any suitable means, as hereinbefore set forth, so that an even coat of wax is placed upon the edge of the heel and thoroughly burnished and polished thereon, said heel afterward being subjected to the action of a padding roll and a brush to obtain a finer polish in a manner well known to those skilled in this art. The wheel being heated by a jet of gas or other suitable means keeps the wax in a liquid condition while it is being applied to the heel.

Having thus described my invention, what I claim and desire by Letters Patent to secure is:

1. A wheel for burnishing and finishing parts of boots and shoes having a continuous yielding metallic periphery, with a helical groove therein extending circumferentially therearound.

2. A heel burnishing and finishing wheel having, in combination, a flexible helical member forming the periphery of said wheel, the median axial line of said helical member extending in the same general direction as the axis of said wheel, and a holder for said member, adapted to hold the adjacent faces of the convolutions of said helical member in contact with each other throughout their entire length, whereby the passage of free wax between said convolutions is prevented.

3. A heel burnishing and finishing wheel having, in combination, a strip of material forming a helical member and constituting the periphery of said wheel, the median axial line of said helical member extending in the same general direction as the axis of said wheel, the outer diameter of each convolution of said helical member being greater than the inner diameters of the convolutions adjacent thereto and a holder for said member adapted to hold the adjacent faces of the convolutions of said helical member in contact with each other throughout their entire length, whereby the passage of free wax between said convolutions is prevented.

4. A heel burnishing and finishing wheel 65 having, in combination, a strip of material forming a helical member and constituting the periphery of said wheel, the median axial line of said helical member extending in the same general direction as the axis 70 of said wheel, and a holder for said helical member adapted to support said helical member with the adjacent convolutions thereof substantially in contact with each other throughout their entire length, the 75 outer edges of said strip being beveled whereby a helical groove is formed in said periphery extending circumferentially there-around and the passage of free wax between said convolutions is prevented. 80

5. A heel finishing wheel having, in combination, a strip of material forming a helical member and constituting the periphery of said wheel, the side faces of said strip being flat, and a holder for said helical 85 member embodying two flanges to which the opposite ends of said helical member are fastened whereby said flat faces may be held in contact with each other throughout their entire length and the passage of free wax 90 therebetween prevented.

6. A heel finishing wheel having, in combination, a strip of material forming a helical member and constituting the periphery of said wheel and a holder for said helical 95 member embodying a hub and two annular flanges fast thereto, the opposite ends of said strip of material being fastened to said flanges.

7. A heel finishing wheel having, in combination, a strip of material bent to form a helical member and constituting the periphery of said wheel and a holder for said helical member embodying a hub with two flanges thereon, the opposite ends of said 105 strip of material being fastened to said flanges, one of said flanges being adjustable on said hub toward and away from the other of said flanges, whereby the adjacent convolutions of said helical member may be 110 held against lateral movement.

8. A heel burnishing and finishing wheel having, in combination, a strip of material forming a helical member and constituting the periphery of said wheel, the median 115 axial line of said helical member extending in the same general direction as the axis of said wheel, the outer edges of said helical member being chamfered to form a helical groove in said periphery, and a holder for 120 said member.

9. A heel burnishing and finishing wheel having, in combination, a strip of material forming a helical member and constituting the periphery of said wheel, the median 125 axial line of said helical member extending in the same general direction as the axis of said wheel, the outer edges of said

helical member being chamfered to form a helical groove in said periphery and a holder for said helical member adapted to support said helical member with the adjacent convolutions thereof substantially in contact with each other.

10. A rotary heel burnishing and finishing tool having, in combination, a rim comprising a strip of material forming a helical member, a holder for said member and a stop on said holder adapted to engage the

inner edges of convolutions of said strip of material and limit the distance to which said convolutions can be moved toward the axial line of said tool.

In testimony whereof I have hereunto set my hand in presence of two subscribing witnesses.

CARL A. MATSON.
